UNITED STATES PATENT OFFICE.

THOMAS J. FLAGG, OF NEW YORK, N. Y.

DESIGN FOR A NECKSCARF.

SPECIFICATION forming part of Design No. 12,299, dated June 7, 1881.

Application filed November 7, 1879. Term of patent 7 years.

To all whom it may concern:

Be it known that I, THOMAS J. FLAGG, of the city, county, and State of New York, have originated and produced a new and original 5 Design for Made-Up Scarfs for Men's Wear, of which the following is a specification, reference being had to the accompanying drawing, forming part thereof.

My invention relates to that class of neck- 10 scarfs in which two crossed aprons are combined with a center piece; and my invention consists in imparting to the various parts of said scarf the form and configuration shown in the accompanying drawing, whereby to secure a scarf of a pleasing and attractive design.

The inner edges, *e*, of the aprons *A A* are straight, and above the point *x*, where the edges cross, and between the same, is exposed 15 a triangular portion of the center or back piece, *B*, which has an upper curved edge, *y*. The lower end of each apron has a straight outer edge, *d*, which merges into a curved edge, *c*, approximating in form an elliptical curve, and extending around the upper end of the apron 20 and terminating at the point where the edge *e* of the apron crosses the edge *y* of the center piece.

G represents the neckband.

The construction above set forth imparts to the scarf a heart-like shape, which is pleasing 30 to the eye, constituting an effective and attractive design.

I make no claim to a scarf having elliptical or curved edges irrespective of the forms of the other portions, as the function of such a 35 construction is embraced in the Letters Patent granted to me on the 2d day of December, 1879, numbered 222,264; but

I claim—

The within-described design for a neckscarf, 40 consisting of crossed aprons and a triangular center piece, *B*, said aprons having each a straight inner edge, *e*, and an elliptical curved edge, *c*, said curved edge beginning at the top and inner side of the apron adjacent to the 45 center piece, and at a point where it is joined by the straight edge *e*, and extending to an outer straight lower edge, as shown in and by the accompanying drawing.

THOS. J. FLAGG.
